Primary Examiner — Elizabeth Albert(57) **CLAIM**

I claim the ornamental design for the can piercing tool, as shown and described.

DESCRIPTION

FIG. 1 is a front view of the can piercing tool showing my new design.

FIG. 2 is a right side view of the claimed design.

FIG. 3 is a left side view of the claimed design.

FIG. 4 is a top view of the claimed design.

FIG. 5 is a bottom view of the claimed design; and,

FIG. 6 is a perspective view of the claimed design.
